[57] CLAIM

The ornamental design for an optical disk cartridge, as shown and described.

DESCRIPTION

FIG. 1 is a front, bottom and right side perspective view of an optical disk cartridge, showing our new design;

FIG. 2 is a front elevational view thereof;

FIG. 3 is a top plan view thereof;

FIG. 4 is a right side elevational view thereof; a left side elevational view is a mirror image of the right side elevational view;

FIG. 5 is a rear elevational view thereof; and,

FIG. 6 is a bottom plan view thereof.
